PYRAZOLONES AND PROCESS OF
PREPARING SAME

Max Schmid, Riehen, Switzerland, assignor to
the firm Society of Chemical Industry in
Basle, Basel, Switzerland

No Drawing. Application July 19, 1939, Serial
No. 285,441. In Switzerland November 6,
1935

3 Claims. (Cl. 260—310)

It has been found that the pyrazolones of the general formula

wherein z stands for a member of the group consisting of hydrogen, Cl, CH_3 , OCH_3 and SO_3H , v stands for a member of the group consisting of NO_2 , NH_2 and NH-acyl , x stands for a member of the group consisting of H, CH_3 , COOR_2 (R_2 standing itself for a member of the group consisting of H, C_2H_5 and CH_3) and phenyl, and y stands for hydrogen or CH_3 , are very valuable products as they permit the manufacture of direct dyeing dyestuffs having new and very valuable properties. Such products may be produced by various methods. It has however been found that they can be produced by a convenient method which proceeds surprisingly easily when starting from amines of the general formula

wherein the groups NH_2 —,

and $-\text{NO}_2$ stand in another position to one another than in ortho-position, and z and v have the above indicated significance. These products can be easily diazotized and what is entirely surprising, be converted into hydrazines of the general formula

wherein the hydrazine residue, the

and the NH_2 -groups occupy the already indicated positions and z and v have again the above indicated significance, by treating them with at

least 1 mol of a salt of sulfurous acid in a weakly alkaline medium whose pH lies advantageously between 7 and 9 and then with a reducing agent, for example a metal selected from the group consisting of iron and zinc, or also with other agents such as stannous chloride, in an acid medium whose pH lies advantageously between 6.5 and 2. When the first stage of the reduction of the diazo-compound has been carried out, viz. the alkaline reduction, wherein a further reducing agent, namely zinc dust, is advantageously added for completing the reaction, there may be obtained in intermediate stages hydrazines of the general formula

wherein the position of the substituents and the meaning of the symbols z and v have already been indicated.

Such hydrazines of the general formula

have the property that the substituted benzoyl-amino group is relatively very firmly linked, so that when treated with acid saponifying agents they are converted into hydrazines of the general formula

wherein the hydrazine residue, the

and the NH_2 -groups occupy the already indicated positions and z and v have again the above indicated significance. These new hydrazines can be converted with the most various β -ketone-acid esters or carbonyl acid esters, for instance formyl-acetic ester, acetoacetic ester, methyl and ethyl-esters of oxalacetic acid, benzoylacetic ester, terephthaloyl-di-acetic ester, para-chloro-ben-

zoyl acetic ester, into pyrazolones which correspond to the general formula

5

10 wherein the pyrazolone nucleus, the

15 and the NH₂-groups occupy the already indicated positions, z and v have again the already indicated significance, and x stands for a member of the group consisting of H, CH₃, COOR (R standing for a member of the group consisting of H, 20 CH₃ and C₂H₅) and phenyl. These pyrazolones 20 may be used for the manufacture of dyestuffs either as such or after the free NH₂-group has been treated with acylating agents whereby there are obtained pyrazolones of the general formula

25

30

wherein x, z and v have the above indicated significance. Finally, the products of the first stage of the reduction of the diazotized products of the above explained general formula

35

40

may be condensed to pyrazolone derivatives with the keto or carbonyl acid esters after splitting off the sulfonic group attached to the hydrazine residue, that is to say to compounds of the general formula

45

50

wherein the position of the substituents and the meaning of the symbols z and v have already been explained. All these new pyrazolones are light colored powders which dissolve in dilute caustic alkalis, if desired after addition of some alcohol, to yellow solutions from which they may be precipitated by acidifying. With diazo compounds these pyrazolones yield dyestuffs which, as mentioned above, may be characterized by valuable and hitherto unknown properties.

60 The following examples illustrate the invention, the parts being by weight:

Example 1

65

25.7 parts of finely powdered para'-nitrobenzoyl-meta-phenylenediamine of the formula

70

are suspended in 50 parts of water, 30 parts of hydrochloric acid of specific gravity 1.15 and ice. A solution of 7 parts of sodium nitrite in 20 parts of water is entered in drops into this mixture

5 at 0-10° C., the whole is stirred for one hour, then filtered and the diazonium chloride is washed with a little ice water. The suspension is then stirred with 100 parts of water and poured, while stirring, into a cooled mixture consisting of 65 parts of bisulfite solution of 40 per cent strength, 10 parts of sodium carbonate and 10 parts of caustic soda solution of 36° Bé. Such a mass has a pH of about 7.5 to 8.5. The mixture is stirred overnight, then heated to 80° C., 20 parts of acetic acid of 30 per cent strength are added thereto and 5 parts of zinc dust are gradually strewn in. The solution becomes light yellow after a short time. It is filtered from the zinc dust in excess and sodium carbonate is 15 added until the solution has a feebly alkaline reaction. By salting out there is obtained the sodium salt of the hydrazine sulfonic acid of the formula

20 which is colored light yellow and is easily soluble 25 in water.

When dissolving 1 part of this sodium hydrazine sulfonate in 10 parts of water of 60° C., adding 3 parts of hydrochloric acid of specific gravity 1.15 and stirring the solution for 45 minutes 30 at 60-65° C., the hydrochloride of the meta-(para'-nitrobenzoyl)- aminophenyl hydrazine of the formula

35 is precipitated on cooling as a brown-yellow 40 coarsely grained powder which is also sparingly soluble in hot water.

By reduction of the meta-(para'-nitrobenzoyl)- aminophenyl hydrazine sulfonic acid of the formula

45 with iron and acetic acid there is obtained the 50 corresponding aminohydrazine sulfonic acid of the formula

55 This reduction may be effected for instance as follows:—

35.2 parts of the hydrazine-N-sulfonic acid of the formula

65 are gradually introduced in the form of the sodium salt at 70-75° C. and while vigorously stirring into a mixture rendered active with about 10 parts of acetic acid of 30 per cent strength and consisting of 30 parts of iron and 70 100 parts of water. When complete decolorization can be ascertained sodium carbonate is added to the reduction liquor until it reacts alkaline. The whole is filtered hot, i. e., at about 75-80° C. in order to remove the iron mud 75

and the sodium salt of the hydrazine-N-sulfonic acid of the formula

is separated from the filtrate by addition of common salt. This hydrazine-N-sulfonic acid is saponified by dilute hydrochloric acid at 10 60-65° C. to the meta-(para'-aminobenzoyl)-aminophenylhydrazine of the formula

which is easily soluble as hydrochloride and 20 which is isolated by neutralizing the hydrochloric acid solution with sodium carbonate in the cold.

When using instead of para'-nitrobenzoylmeta-phenylenediamine, meta'-nitrobenzoylmeta-phenylene diamine, para'-nitrobenzoylmeta-phenylene diamine or meta'-nitrobenzoylmeta-phenylene diamine, there are obtained 25 similar products, for example products of the formulas

40 *Example 2*

33.7 parts of para'-nitrobenzoyl-para-phenylene-diamine-ortho-sulfonic acid the formula

50 are dissolved in 70 parts of water and 12 parts of caustic soda solution of 36° Bé. to which are added 7 parts of sodium nitrite. This solution is poured into a mixture of 42 parts of hydrochloric acid of specific gravity 1.15 and so much ice that the temperature does not exceed 10° C. The 55 whole is stirred for a further hour at 0-10° C., and then filtered. The diazonium chloride thus obtained is suspended in 100 parts of ice water and the suspension is poured into a cooled mixture consisting of 65 parts of bisulfite solution of 40 per cent. strength, 16 parts of sodium carbonate and 10 parts of caustic soda solution of 36° Bé. The whole is stirred overnight, then heated to 80° C., 25 parts of acetic acid of 30 per cent strength are added thereto and 5 parts of 60 zinc dust are gradually strewn in until the color of the solution changes to yellow. The hydrazine sulfonic acid of the formula

is obtained from the filtered solution by salting out.

75 By heating with dilute hydrochloric acid the

hydrazine sulfonic acid is saponified to the hydrazine of the formula

When reducing the nitrohydrazine sulfonic acid of the formula

15 with iron and acetic acid in the manner indicated above, the corresponding aminohydrazine sulfonic acid of the formula

is obtained, which is converted into the hydrochloride of the hydrazine of the formula

by heating with dilute hydrochloric acid.

By neutralizing the hydrochloric acid with sodium carbonate there is obtained the sodium salt of the hydrazine sulfonic acid.

When replacing in Example 1 the para- or meta-nitrobenzoyl phenylene diamine by the corresponding 3-nitro-4-methyl benzoyl phenylene diamine of the formula

or

45 or in Example 2 the para'-nitrobenzoyl-para-phenylene-diamine-ortho-sulfonic acid by the corresponding sulfonic acids of the formula

or

60 the following hydrazines may be obtained over the N-sulfonic acids:

5 *Example 3*

27.7 parts of finely powdered 1-(para'-nitrobenzoyl)-amino-4-amino-3-chlorobenzene of the formula

15 are suspended in 100 parts of water, 30 parts of hydrochloric acid of specific gravity 1.15 and ice. An aqueous solution of 7 parts of sodium nitrite is added to this mixture at 5-10° C. and the whole is stirred until diazotization is complete.

20 The diazo paste is added while stirring to an ice cooled mixture consisting of 65 parts of bisulfite solution of 40 per cent strength and 15 parts of sodium carbonate, care being taken that the action of the sulfite on this diazo compound takes place always in a medium of a pH of about 25 7 to 8.5. The mixture is stirred overnight, heated to 70-80° C. and salted out. The yellow precipitate which has separated is suspended in about 100 parts of water of 80° C., about 20 parts of acetic acid of 30 per cent strength are added 30 to this mixture and zinc dust is gradually strewn in until it is of light yellow color. The mixture is filtered to remove the zinc dust in excess, and sodium carbonate is added until the solution has 35 a feebly alkaline reaction whereupon the N-sulfonic acid of the formula

40 is salted out as sodium salt.

When introducing the same at about 60° C. into a mixture of iron filings and water rendered caustic with some hydrochloric acid or acetic acid, and stirring the mixture until it is completely decolorized, adding sodium carbonate until the reduction liquor reacts clearly alkaline, filtering the whole to remove the iron mud and salting out the filtrate, there is obtained the 1-(4'-aminobenzoylamino)-4-hydrazino-N-sulfo-3-chlorobenzene of the formula

55 in the form of the sodium salt.

When carefully treated with acids, for example hydrochloric acid, at 70-80° C., the N-sulfo-group is split off with formation of the salt of the 60 hydrazine of the formula

65 *Example 4*

33.7 parts of meta'-nitrobenzoyl-para-phenylene-diamine-ortho-sulfonic acid of the formula

70 are dissolved in 60 parts of caustic soda solution of 36° Bé. and 120 parts of water, to which are

then added 7 parts of sodium nitrite. This solution is poured into a mixture of 90 parts of hydrochloric acid of specific gravity 1.15 and so much ice that the temperature does not exceed 5° C. The diazonium salt is filtered after 1 hour, suspended in 150 parts of ice water and poured into a cooled mixture consisting of 65 parts of sodium bisulfite of 40 per cent strength, 10 parts of caustic soda solution of 36° Bé., 20 parts of sodium carbonate and 100 parts of water. The whole is stirred overnight at 0-5° C. whereupon it is heated to 60° C. and 30 parts of hydrochloric acid of specific gravity 1.15 are added thereto so that the solution reacts very feebly acid to Congo. The solution is then gradually poured into a mixture consisting of 30 parts of iron in 100 parts of water and 10 parts of acetic acid of 30 per cent strength, the temperature amounting to about 60° C. After complete decolorization there are added 15 parts of sodium carbonate and the whole is filtered to remove the iron mud. In the solution exists the sodium salt of the hydrazine-N-sulfonic acid of the formula

25 For saponification the solution is heated to 60° C. and mixed with 180 parts of hydrochloric acid of specific gravity 1.15 so that an acid of about 5 per cent strength is formed. This is stirred for 1/2 hour at 60-65° C. On cooling the hydrazine of the formula

35 crystallizes as hydrochloride.

40 *Example 5*

30.8 parts of the para-(para'-nitrobenzoyl)-aminophenyl-hydrazine of Example 1 are dissolved in the heat in 150 parts of alcohol and 53 parts of sodium carbonate solution of 10 per cent strength. To this solution are added 10 parts of acetic acid of 30 per cent strength and 13 parts of acetoacetic ester and the whole is 45 heated for one hour to feebly boiling. It is then filtered and the solution is mixed at 60-65° C. with 30 parts of caustic soda solution of 36° Bé. Stirring is continued for a further hour at this 50 temperature and the pyrazolone of the formula

55 is precipitated from the filtered and cooled solution. This pyrazolone can be reduced by sodium sulfide at 80° C. to the corresponding aminopyrazolone of the formula

65 This may be also obtained directly by condensing the aminohydrazine of the formula

in an alcoholic or aqueous solution with acetoacetic ester.

Similar products are obtained when using 5 formylacetic esters, substituted or unsubstituted benzoylacetic esters, sodium oxalacetic acid ethyl or methyl esters, terephthaloyldiacetic ester and the like instead of acetoacetic ester. These products are distinguished from the first 10 and the second formula of this example in that the $-\text{CH}_3$ group of the pyrazolone nucleus is replaced by H, phenyl, COOH, COOCH₃, COOC₂H₅ as for example

Example 6

39.5 parts of the hydrazine of Example 2 of the formula

35 are dissolved in 300 parts of water and 16 parts of sodium carbonate. To this solution is added a solution of 21 parts of sodium oxalic acetic ester in 100 parts of water and the whole is stirred for 1 hour to 80° C. 12 parts of caustic soda solution of 36° Bé. are then added and stirring is continued for 1/2 hour at about 60° C., whereupon the mixture is filtered after cooling. The 40 pyrazolone of the formula

50 may be precipitated by acidifying. If this pyrazolone is heated for 2 hours to 70-80° C. with caustic soda solution of about 10 per cent strength and then allowed to cool, the free pyrazolone carboxylic acid of the formula

is precipitated by acidifying.

60 *Example 7*

If the disodium salt of the amino-pyrazolone of the formula

70 (obtained by condensing the hydrazine of the formula

75 in an aqueous solution with sodium oxalacetic

ester, saponifying the pyrazolone carboxylic acid ester and then reducing the nitro-group with sodium sulfide) is dissolved in water, adding in 5 drops to this solution at 10-15° C. so much acetic acid anhydride that the free amino-group 5 can no longer be detected, and filtering, there is obtained a pyrazolone of the formula

Instead of acetic acid anhydride there may also 15 be used benzoyl chloride and other acid chlorides or organic halogen compounds having such an action, for instance chloroformic ester, cyanuric chlorides, arylsulfochlorides and the like.

By using the parent materials indicated in 20 Examples 1 to 4 for the manufacture of the corresponding hydrazines over the hydrazine-N-sulfonic acids, the corresponding pyrazolones can be produced by condensing these hydrazines with the β -keto- or carbonyl-carboxylic acid esters cited for example in Example 5.

25 Further it is possible first of all to reduce the nitro-group of a nitrophenylhydrazine sulfonic acid to the amino-group, acidify the latter with the nitroaroyl chlorides and if necessary reduce the nitro-group or eliminate the N-sulfonic group by acid saponifying agents. The course 30 of the reaction is then the following:

In the operations described above there may 60 be used as parent compounds inter alia compounds of the following formulas

This application is a continuation-in-part of my application Serial No. 108,902, filed November 2, 1936.

20 What I claim is:

1. The pyrazolones of the general formula

wherein the pyrazolone nucleus and the

stand in another than in ortho-position to one another, x stands for a member of the group consisting of H, CH₃, COOR, R standing itself for a member of the group consisting of H, CH₃ and C₂H₅, and phenyl, y stands for a member of the group consisting of NO₂, NH₂ and NH-acyl, z stands for a member of the group consisting of hydrogen, Cl, CH₃, OCH₃ and SO₃H, and v stands for a member of the group consisting of

hydrogen and CH₃, which products are light colored powders capable of dissolving in water on addition of alcohol and caustic alkalies and capable of coupling with diazo-compounds to form azo dyestuffs.

2. The pyrazolones of the general formula

wherein x stands for a member of the group consisting of H, CH₃, COOR, R standing itself for a member of the group consisting of H, CH₃ and C₂H₅, one z stands for H and the other z stands for a sulfonic group, one v stands for H and the other v stands for a member of the group consisting of NO₂, NH₂ and NH-acyl, and wherein the pyrazolone nucleus and the

stand in another position to one another than in ortho-position, which products are light colored powders dissolving in water on addition of caustic alkalies and coupling with diazo-compounds to form azo dyestuffs.

3. The product of the formula

which is a light colored powder dissolving in water on addition of alkalies and coupling with diazo-compounds to form azo dyestuffs.

MAX SCHMID. 40
